WALL-BUILDING MACHINE

John H. Magdiel and Daniel H. Magdiel,
Los Angeles, Calif.

Application May 13, 1949, Serial No. 93,034

6 Claims. (Cl. 25—131)

1

The invention relates to improvements in the type of wall-building machine in which two main mold sides are fastened together and held in position by a clamping assembly which resists the pressure of tamping semi-soft concrete, in forming a wall.

As is well known, concrete walls can be built by tamping damp aggregate into a wall mold, which, when filled, is at once moved forward to be filled again; but overlapping the just made section about six inches, thus forming continuous horizontal courses, which being tamped of damp, not wet, concrete, stand up without sagging when mold forms are removed.

The idea of building walls in courses of moist, not wet, concrete by tamping it in place, is not by any means new. In fact, it was one of the earliest modes of using concrete as a building material. The method generally employed in forming the wall was to use a set of planks generally in the form of a crib, bolt them together, tamp them full, let it set awhile, then unscrew the bolts and raise the whole crib form up a foot or more and proceed to fill it again. It sounds simple to the inexperienced but the cost of releasing, lifting and resetting, make these walls rather expensive. With our moveable wall mold and by filling and tamping short sections of wall and moving the collapsible mold ahead its own length, minus the overlap, saves much of this time and expense, especially where tension straps and lock levers are used instead of rods and bolts and nuts. However, as stated above, to get strength and rigidity in this way is generally paid for in weight and clumsiness. We solve this dilemma with our novel improvements in this invention.

There have been made other somewhat similar wall-building apparatuses, including one for which Daniel H. Magdiel, one of the present inventors or applicants, was granted Patent No. 945,182. Through experience we have found that the mold sides of such other apparatuses, if made light enough to be conveniently handled while building a wall, are not strong enough to withstand the pressure caused by tamping the semi-soft concrete.

We have therefore, in this invention, contrived to increase and practically double the rigidity without adding weight to the mold side as lighter materials can be used.

We have also found in said Daniel H. Magdiel's former wall mold, that the whole clamp assembly was defective, especially the front clamp arm with top, as formerly made of one piece of channel iron. This was bent to form the spreader top

2

as well as the side of the clamp arm, but this afforded no means of adjustment, so that, when, as often happened, heavy tamping would spring the clamp arm and throw the mold sides out of alignment. Likewise, the locking lever and double tension strap in the ways and shapes as formerly constructed, were not rigid enough to hold the mold sides firmly in correct position.

In our new, novel, and improved wall-building machine, we increase the strength yet reduce the weight of the mold sides by various novel means, hereinafter more fully described and also eliminate the defects in the former clamping assemblies.

15 In drawings Figure I, is an elevation of a portion of the front mold side with front clamp arm attached. Figure II is an elevation of an end view of the whole assembly. Figure III is a plan view of the lower flanges of a mold side with stiffener cleat and reinforcing rod. Figure IV is a rear elevation of the rear clamp arm. Figure V is an elevation of an enlarged portion of rear clamp arm with one side cut away to show springstrap holding up mold side with clamp sleeve. Figure VI is a rear elevation of Figure V also showing clip. Figure VII is a plan view of a cross section of Figures V and VI on line VII—VII. Figure VIII is an end view of flange rolled over a reinforcing rod.

20 Referring to Figures I, II, III and IV, Arabic numeral 1 is the side of the mold, made of a thin flat, approximately rectangular metal sheet, about two inches wider in its middle part, bent on its lower and upper edges outward at right angles to form a main stiffening flange 2—2, preferably about one and one-half inches wide at each end and two and one-half inches wide in the middle. These main flanges 2—2, are again bent at right angles on their outer edges to form a smaller flange 3 on the main flange 2. In the bending process a parallel portion is formed at the middle of flange 2 where the main, preferably wood, stiffener cleat 4 is located. On this the clamp arms 5—5 are fastened. One or more light cleats 6, preferably of wood, are also placed on each side of the center, to prevent bending outward of the light metal sheet 1.

25 To further stiffen the mold sides, we insert spring steel rods 7, preferably three-sixteenths of an inch in diameter, in the outer corners of flanges 2 and 3. These rods are long enough to force the mold sides to bend slightly outward in the center, as we make the ends of the rods and mold sides coincide. We next weld the rod 7 tight in the end corners of flanges 2 and 3 and

fold flange 3 over rod 7 and flatten the remainder of flange 3 onto main flange 2 resulting in a strong resilient yet light mold side.

In the new clamp assembly Figure II we overcome the disadvantage of former clamp frames as mentioned above, first by making the front clamp arm 5 upright and separate from the thrust members 10-11-13 which gives adjustment means as compared with the old front arm made in one piece without adjustment means. Secondly, by using one tension strap instead of two. Thirdly, by having the rear clamp arm detachable from the mold side, instead of bolted solid as formerly. The front and rear upright clamp arms 5F and 5R we make of specially formed and shaped channels as shown in the drawings. In the upper end of the front arm 5F we weld or fasten a short pipe nipple 8; onto this nipple we screw an L, preferably a reducer L 9. Into the horizontal end of this L, we screw a short nipple 10 having left-handed threads on its outer end. Onto this nipple end, we screw a left and right coupling 11 preferably pierced with two holes 12 for insertion of a turning rod or key. Into the outer right hand threads of this coupling 11 we screw the main thrust or spreader pipe 13. This pipe-spreader has holes 14, equally spaced and at 90 degrees other holes equally spaced half-way between the first holes. These holes are for adjustment to different wall thicknesses. Bolt 15 is inserted through one of these holes and hinges the spreader pipe 13 to the forked top of the rear clamp arm 5R. It will be seen by referring to Figure II that when right and left coupling 11 is turned one way or the other, the pipe 13 and the nipple 10 will be drawn together or forced apart so that a small adjustment can be made in the length of the spreader or thrust members 10-11-13, thus changing the vertical alignment of the mold-sides held by the tension strap 16.

The locking lever or lever hand 17 Figures I and II is a great improvement over former locking devices made of a twisted iron rod. The new handle is light and strong made hollow of pressed steel and reinforced at its fulcrum points with double steel clips 18 fastened to the main body 17 and swinging on bolt 19. This bolt goes through the clamp arm side under the tension strap 16 and protrudes through the opposite clamp arm side to allow nut 20, see Figure I, to hold the clamp arm sides from spreading when pressure is applied by locking lever 17 to tension strap 16.

It will be observed in Figure II where part of clamp arm side has been cut away, that the tension strap 16 ends on the right in a forty-five degree bend, having a hole in the end. This end enters the locking lever and is fastened with bolt 21. This angle extension makes it possible to bring lever handle down to a locking position without interfering with fulcrum bolt 19 and its other function of keeping clamp arm sides from spreading when pressure is applied.

The narrow slot 22 near the middle of clamp arm 5F through which tension strap 16 passes, see Figure I, is elongated, to allow tension strap 16 to rise up when locking lever 17 is brought up (see dotted lines Figure II) to release tension and push outer or rear clamp arm 5H and its mold side away from the tamped-in wall before moving the whole apparatus along the wall ready to again be filled with semi-soft concrete and tamped down solid. This tension strap 16 also has evenly spaced holes 23 which correspond with holes 14 in spreader pipe 13 above for adjustment of machine to make walls of varying thickness.

Through one of the holes in the tension strap, bolt 24 with nut 25 is inserted and holds the whole assembly in alignment. To prevent bolt 24 from bending when pressure is applied, we insert wedge clip 26. This is a double-pronged wedge shaped clip passing over or straddling tension strap 16 and pressing between bolt 24 and body of rear clamp arm.

Under certain conditions, especially where many perpendicular reinforcing rods are used in walls, it has been found desirable to remove the rear mold side from the rest of the assembly and to immediately replace it after clamp assembly with front mold side is moved forward to build another section of wall. To accomplish this with speed and yet have a rigid device, we provide the rectangular beveled clasp 27. This clasp is formed to fit the rear clamp arm 5R at the proper height and extend over the central stiffener cleat 4 to which it is bolted but leaving the clasp's rear part open. The rear face of the open part is preferably bent inward for added stiffness and to moderately hug the sides of the clamp arm 5R as shown best in Figures V and VII. Extending above this clasp and fastened to the clamp arm is a spring strap 28 with a small lug 29 attached near its lower end. This spring and lug engage the lower edge of the clasp 27 and thereby hold the mold side, to which the clasp is fastened, in position until the spring is pressed down, it then releases the clasp and the whole mold side is loose and removable.

To further hold the clamp arm and mold side in alignment and rigid, we use a large headed bolt or screw 30, Figures II and IV fastened in the stiffening cleat 4 on the mold side, the head of this bolt being just far enough out to admit the slotted end 31 of the clamp arm 5R to pass under bolt head 30. The slot 31 in the lower end of clamp arm 5R is forked or V-shaped for ready admittance and good side contact.

We claim:

1. A wall building machine comprising, in combination, a front mold side and a rear mold side, each made of a thin sheet of approximately rectangular shape, comprising on both its longer edges, at right angles, main stiffening flanges, and comprising also on the outer edges of each main flange a second narrower flange which is folded over a stiff steel rod in each outer corner of the two flanges, said rods being a little longer than the flanges, so that by forcing the ends of the flanges to coincide with the ends of the longer rods, the side of the mold is bowed slightly outward in the middle, also three cleats, extending on each mold side from upper to the lower main flanges.

2. A wall building machine comprising in combination a front mold side and a rear mold side, each made of a thin sheet of approximately rectangular shape, comprising on both its longer edges, at right angles, main stiffening flanges, and comprising also on the outer edges of each main flange a second narrower flange which is folded over a stiff steel rod in each outer corner of the two flanges, said rods being a little longer than the flanges, so that by forcing the ends of the flanges to coincide with the ends of the longer rods the side of the mold is bowed slightly outward in the middle, also three cleats, extending on each mold side from upper to the lower main flanges; a front clamp arm having an elongated slot in its middle and fastened to the center stiffening cleat of the front mold side, a locking lever comprising an approximately right angle

double end, a fulcrum bolt through about the middle of said clamp arm and through the angle ends of the locking lever to support the latter and allow it to be raised or lowered as desired, a perforated tension strap with an angular end, connecting the lever handle with the rear clamp arm.

3. A wall building machine comprising the combination of claim 2 and comprising in addition: A spreader assembly comprising an L 10 screwed on a nipple fastened in the top of the front clamp arm, a right and left nipple screwed into said L, a right and left coupling screwed on the end of said second nipple, an extension pipe with adjustment holes through it screwed into said coupling.

4. A wall building machine comprising the combination of claim 2 and comprising in addition: A spreader assembly comprising an L 15 screwed on a nipple fastened in the top of the front clamp arm, a right and left nipple screwed into said L, a right and left coupling screwed on the end of said second nipple, an extension pipe with adjustment holes through it screwed into said coupling: A rear clamp arm having a forked top and an elongated slot through its middle and to the forked top of which a spreader assembly is fastened by a bolt and through the middle of which a tension strap is fastened by a bolt, a flat spring with a lug near its lower end, said rear clamp arm with a short V-shaped slot in its lower end.

5. A wall building machine comprising in combination all of claim 2 and comprising in addition: A spreader assembly comprising an L 20 screwed on a nipple fastened in the top of the front clamp arm, a right and left nipple screwed into said L, a right and left coupling screwed on the end of said second nipple, an extension pipe with adjustment holes through it screwed 25 into said coupling: A rear clamp arm having a forked top and an elongated slot through its middle and to the forked top of which a spreader assembly is fastened by a bolt and through the middle of which a tension strap is fastened by a bolt, a catch comprising a flat spring with a lug near its lower end, said rear clamp arm with a short V-shaped slot in its lower end; a wedge-shaped double-clip straddling the tension strap and forced between said bolt and the outer side of 30 rear clamp arm; a U-shaped clasp, its free ends fastened to the middle cleat of the rear mold side with an open rear part, large enough to allow the lower part of the rear clamp arm to readily enter it, its rear face bent inward and its lower edge fitted to engage the above mentioned spring strap catch.

into said coupling; a rear clamp arm having a forked top and an elongated slot through its middle and to the forked top of which a spreader assembly is fastened by a bolt and through the middle of which a tension strap is fastened by a bolt, a flat spring with a lug near its lower end, said rear clamp arm with a short V-shaped slot in its lower end; a wedge-shaped double-clip straddling the tension strap and forced between said bolt and the outer side of rear clamp arm.

6. A wall building machine, comprising the combination of claim 2 and in addition: A spreader assembly comprising an L 20 screwed on a nipple fastened in the top of the front clamp arm, a right and left nipple screwed into said L, a right and left coupling screwed on the end of said second nipple, an extension pipe with adjustment holes through it screwed into said coupling: A rear clamp arm having a forked top and an elongated slot through its middle and to the forked top of which a spreader assembly is fastened by a bolt and through the middle of which a tension strap is fastened by a bolt, a catch comprising a flat spring with a lug near its lower end, said rear clamp arm with a short V-shaped slot in its lower end; a wedge-shaped double-clip straddling the tension strap and forced between said bolt and the outer side of 25 rear clamp arm; a U-shaped clasp, its free ends fastened to the middle cleat of the rear mold side with an open rear part, large enough to allow the lower part of the rear clamp arm to readily enter it, its rear face bent inward and its lower edge fitted to engage the above mentioned spring strap catch.
